UNITED STATES PATENT OFFICE

OTTO LANDY, OF CHICAGO, ILLINOIS

DESIGN FOR AN ASH TRAY

Application filed January 30, 1933. Serial No. 47,052. Term of patent 3½ years.

To all whom it may concern:

Be it known that I, OTTO LANDY, a citizen of the United States, residing at 1547 South Central Park Avenue, in the county of Cook and State of Illinois, have invented a new, original, and ornamental Design for an Ash Tray, of which the following is a specification, reference being had to the accompanying drawing, forming a part thereof.

Fig. 2 is a vertical cross-sectional view of my said ash tray.

I claim:

The ornamental design for an ash tray substantially as shown.

OTTO LANDY.
